US00D973090S

(12) United States Design Patent (10) Patent No.: US D973,090 S
(45) Date of Patent: * Dec. 20, 2022

(54) DISPLAY SCREEN OR PORTION THEREOF
WITH GRAPHICAL USER INTERFACE

(71) Applicant: salesforce.com, inc., San Francisco, CA (US)

(72) Inventor: Joey Lomanto, Dundas (CA)

(73) Assignee: Salesforce, Inc., San Francisco, CA (US)

() Term: 15 Years

(21) Appl. No.: 29/778,006

(22) Filed: Apr. 9, 2021

(51) LOC (13) Cl. 14-04

(52) U.S. Cl.

USPC D14/487

(58) Field of Classification Search

(57) CLAIM

The ornamental design for a display screen or portion thereof with graphical user interface, as shown and described.

DESCRIPTION

The FIGURE is a front view of a display screen or portion thereof with graphical user interface showing the claimed design.

The broken lines in the FIGURE show a display screen or portion thereof, and form no part of the claimed design.

1 Claim, 1 Drawing Sheet
